UNITED STATES PATENT OFFICE.

FRANK H. VAN HOUTEN, OF BEACON, NEW YORK.

DESIGN FOR A LOAF OF BISCUIT OR ROLLS.

49,941.

Specification for Design.

Patented Nov. 21, 1916.

Application filed May 29, 1915. Serial No. 31,295. Term of patent 3½ years.

To all whom it may concern:

Be it known that I, FRANK H. VAN HOUTEN, a citizen of the United States, residing at Beacon, in the county of Dutchess and State of New York, have invented a new, original, and ornamental Design for a Loaf of Biscuit or Rolls, of which the following is a specification, reference being had to the accompanying drawings, in which—

Figure 1 is a plan view of a loaf of biscuit or rolls showing the new design. Fig. 2 is a perspective view of the same.

The design for a loaf of biscuit or rolls is circular in outline and consists of a central roll or biscuit substantially circular in con-

tour divided into three sector shaped portions, and a series of rolls or biscuits surrounding said central roll and extending radially therefrom, each of the division lines formed by the three sector shaped portions of the central roll and the dividing line formed by the two outer rolls adjacent each of said first mentioned lines forming a substantially straight line extending from the center to the outer edge of the loaf.

I claim:

The ornamental design for a loaf of biscuit or rolls, substantially as shown and described.

FRANK H. VAN HOUTEN.
